UNITED STATES PATENT OFFICE

HUGH E. DRURY, OF WORCESTER, MASSACHUSETTS, ASSIGNOR OF ONE-HALF TO WILLIAM H. McTIGHE, OF WORCESTER, MASSACHUSETTS

HEADLIGHT

Application filed April 30, 1930. Serial No. 448,531.

This invention relates to a headlight particularly designed for use on automobiles but also adapted for many other purposes.

It is the general object of my invention to provide a construction by which a headlight may be quickly and easily restored to operative condition after a filament in the headlight bulb has burned out or broken.

A further object is to provide a construction by which operative conditions may be restored without removing the bulb from the headlight or disturbing the focusing thereof.

My invention further relates to arrangements and combinations of parts which will be hereinafter described and more particularly pointed out in the appended claims.

A preferred form of the invention is shown in the drawings, in which

Fig. 1 is a sectional side elevation of my improved headlight;

Fig. 2 is an enlarged transverse sectional elevation of a portion of the headlight bulb; and

Fig. 3 is an enlarged side elevation of certain parts.

Referring to the drawings, I have shown a portion of a reflecting casing 10 in which a bulb 11 is mounted. The bulb 11 is provided with a shank portion 12 fitting into a fibre socket 13 and secured therein by the usual stud 15 and bayonet lock 16. The bulb 11 is of special construction and is provided with a plurality of filaments 20, angularly spaced apart and all converging on a common support 21. The support 21 also forms one terminal of the bulb and is extended through the shank 12 to a stud or contact member 22 at the outer end thereof.

A series of contact plates 25 (Fig. 2) are spaced about the periphery of the shank 12 and one terminal of each of the filaments 20 is connected to one of the contact plates 25. A spring-pressed contact plunger 30 (Fig. 1) is mounted in a fibre bushing 32 which is surrounded by a fibre cap 33. Each of the contact plates 25 is preferably grooved longitudinally, as indicated at 35 in Fig. 2, and the rounded inner end of the plunger 30 seats itself in the groove 35 of the plate 25 which is operatively positioned. The plunger 30

is connected to a wire 36 forming one side of a lighting circuit and a conductor 37 forming the other side of the lighting circuit is grounded on the casing 10.

A metal rod 40 is secured in the outer end of the fibre socket 13. A metal plunger 41 is slidably mounted between the socket 13 and the rod 40 and yieldingly engages the contact 22 at the outer end of the shank 12. A spring 42 actuates the plunger 41 and electrically connects the plunger to the metal rod 40.

A metal cap 45 is threaded on the outer end of the rod 40 and engages an inwardly extending flange 46 at the outer end of a tubular extension 50 of the casing 10. A relatively heavy spring 52 is interposed between the outer end of the socket 13 and the flange 46 and is effective to hold the cap 45 firmly seated against the flange 46.

A lighting circuit is thus completed from the wire 36 through the plunger 30 to one of the contact plates 25 and filaments 20, and is continued through the common support 21 to the contact member 22, plunger 41, spring 42, rod 40, cap 45, tubular extension 50 and casing 10 to the wire 37.

If this circuit is broken by the burning out or breaking of the particular filament 20 which is in use, the circuit may be restored by grasping the cap or nut 45 and turning the socket angularly to bring the plunger 30 in contact with another one of the contact plates 25.

In order to preserve the angular adjustment, the outer end of the tubular extension 50 is provided with a series of cam recesses or notches 55 (Fig. 3) adapted to receive a cam-lug or projection 56 on the cap 45.

When the cap is turned, the cap and socket will be forced outward, compressing the spring 52 as the projection 56 is moved out of one of the recesses 55, but the parts will return to their previous axial relation as soon as the projection 56 enters the next notch or recess 55.

The bulb 11 will thus be given angular advance movements corresponding to the angular spacing of the several filaments 20 and contact plates 25. In the drawings, I have shown four filaments and contact plates but

it will be understood that this number may be increased or decreased as desired.

The socket 13 and bulb 11 may be adjusted axially for focusing purposes by turning the nut 45 on the metal rod 40, it being evident that the spring 52 will advance the bulb into the reflector 10 as far as is permitted by the position of the cap or nut 45.

When the bulb is correctly focused, a cotter-pin 60 may be inserted through openings in the sides of the cap 45 and through an elongated slot 61 in the rod 40. After the pin 60 is inserted, the bulb and socket may be turned angularly by the cap 45 without changing the adjustment of the cap 45 on the rod 40 and consequently without disturbing the focusing adjustment of the bulb 11.

It will thus be seen that I have provided a headlight construction by which a new filament may be placed in operative position and the lighting circuit may be restored without disturbing the focusing of the bulb and without the necessity of removing a lens or otherwise obtaining access to the interior of the reflecting casing 10. A headlight may thus be restored to operative condition with the least possible delay and without the use of tools or the removal of any part.

Having thus described my invention and the advantages thereof, I do not wish to be limited to the details herein disclosed, otherwise than as set forth in the claims, but what I claim is:—

1. In a headlight, a casing, a bulb angularly adjustable in said casing, said bulb having a plurality of filaments with one terminal of each filament connected to a common contact and with the other terminal of each filament connected to one of a series of separate contacts spaced about the shank of said bulb and each formed with a longitudinally extending groove, contacting means continuously engaging said common contact, and a spring contact plunger yieldingly engaging an operatively positioned separate contact in the longitudinal groove thereof to complete a circuit through a selected filament.

2. A headlight comprising a casing having a tubular extension, a bulb having a plurality of separate filaments, a socket for said bulb slidably mounted in said casing extension and having a plurality of different selective angular operative positions, a cap angularly and axially movable relative to said casing extension, means to secure said cap in adjusted axial and angular relation to said socket, whereby said cap is made effective for turning said socket and bulb to different angular positions in said casing extension, contact means engaging a different bulb filament in each different angular position of said socket and bulb, yielding means to move said cap axially into engagement with the end of said casing extension, and means to hold said cap, socket and bulb as a unit in different selected

angular positions in said casing extension but in a uniform axial position.

3. A headlight comprising a casing having a tubular extension, a bulb having a plurality of separate filaments, a socket for said bulb slidably mounted in said casing extension and having a plurality of different selective angular operative positions, a cap angularly and axially movable relative to said casing extension, means to secure said cap in adjusted axial and angular relation to said socket, whereby said cap is made effective for turning said socket and bulb to different angular positions in said casing extension, contact means engaging a different bulb filament in each different angular position of said socket and bulb, yielding means to move said cap axially into engagement with the end of said casing extension, and means to hold said cap, socket and bulb as a unit in different selected angular positions in said casing extension but in a uniform axial position, said latter means comprising a positioning projection and cooperating recesses on adjacent faces of said cap and casing extension.

In testimony whereof I have hereunto affixed my signature.

HUGH E. DRURY.
